(57) **CLAIM**

The ornamental design for a lapel pin, as substantially shown and described.

DESCRIPTION

FIG. 1 is a perspective front view of a lapel pin showing my new design;

FIG. 2 is a perspective rear view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in the drawings represent portions of the lapel pin and form no part of the claimed design.
